UNITED STATES PATENT OFFICE.

CARL REINHOLDT KOSITZKY, OF BISMARCK, NORTH DAKOTA.

ARTICLE SUPPORT.

Application filed May 17, 1923. Serial No. 639,645.

To all whom it may concern:

Be it known that I, CARL R. KOSITZKY, a citizen of the United States, residing at Bismarck, in the county of Burleigh and State 5 of North Dakota, have invented certain new and useful Improvements in Article Supports; and I do declare the following to be a full, clear, and exact description of the invention, such as will enable others skilled in 10 the art to which it appertains to make and use the same.

My invention has for one object to provide a simple and compact device which may be advantageously used for holding a reference book, such as a telephone directory, and a note pad, provision being made whereby a part of the device which normally holds the pad in place, may be moved to a position in which it forms a rest for the pad, while writing upon the latter, and also permits easy access to the directory or other reference book.

A further object is to provide a novel mounting means for an article support which 25 will normally permit disposition of said support adjacent a wall, but will dispose said support in an inclined position away from the wall when desired.

A still further object is to make provision 30 whereby the device may be converted for use as a shaving cabinet or to hold any desired toilet articles.

With the foregoing in view, the invention resides in the novel subject matter herein- 35 after described and claimed, the description being supplemented by the accompanying drawings.

Figures 1 and 2 are perspective views of 40 the invention in different positions.

Figure 3 is a vertical sectional view of the device in the position disclosed in Fig. 1.

Figure 4 is a side elevation showing the device moved into compact relation with a wall or other support.

Figure 5 is a horizontal sectional view 45 taken substantially on line 5—5 of Fig. 3.

In the drawings above briefly described, the numeral 1 designates a vertical back-plate which is designed primarily to be supported against a wall, for which purpose it 50 may well be provided with openings 2 for the reception of nails or screws 3. Opposite vertical edges of the plate 1 are provided with vertically elongated forwardly 55 extending flanges 4 and a wider horizontal

flange 5 extends from the plate 1 between the lower ends of the flanges 4, the front edge portion of the flange 5 being preferably arched transversely to some extent as indicated at 6, for a purpose to appear.

Upper and lower normally upright links 7 and 8 have their lower ends pivoted at 9 to the flanges 4, while I have shown the upper ends of said links similarly connected at 10 to ears 11 which extend rearwardly 60 from an article-supporting casing 12. This casing normally stands upright at the front edges of the flanges 4 and co-operates with these flanges, with the flange 5 and with the back-plate 1, in forming a receptacle for a 65 note pad or tablet 13. It will be seen by comparing the several views however, that when the casing 12 is moved forwardly and downwardly, it is disposed at an inclined position, in which position, it will effectively 70 serve as a rest for the pad 13, while writing upon the latter. To prevent this pad from falling out of place when the casing 12 is moved forwardly, in case the use of said 75 pad is not needed, a bar or strap 14 may extend between the flanges 4 as shown in Fig. 3.

Movement of the casing 12 to an inclined position, such as that shown in Figs. 1, 2 and 3 is due to the fact that the distance between the pivots 9 is greater than the distance between the pivots 10 and in the present disclosure, the upper links 7 are shorter than the lower links 8. The arrangement is such however that when the casing 12 is moved to its retracted position, 80 as seen in Fig. 4, it will be vertically disposed in front of the flanges 4.

The casing 12 is preferably formed of front and rear sections 15 and 16 hinged together at 17 and when this casing is intended to contain a reference book of any character, metal strips 18 are positioned vertically in the two sections and are anchored at their ends, so that the back and front of the book may be inserted under these strips, 85 thus opening the book for reference when the front section 15 of the casing is opened. These strips also serve to prevent the book from accidentally falling from the casing when the latter is open.

When the device is used as a telephone directory holder, it is desirable to have a list of important phone numbers displayed at the front of the casing 12. For holding such a list, I have shown a frame 19 carried 100

by the front casing section 15, the upper end of this frame being open so that the list and a glass or celluloid cover therefor may be easily inserted. When desired, in 5 case the article is used for other purposes, the frame 19 may contain a mirror.

In order that the invention may be advantageously used to contain toilet articles if desired, I provide the rear casing section 10 16 with means for retaining an article holding plate 20 in place. This plate is intended to extend transversely across the open side of the casing section 16 and it is provided with a plurality of rearwardly extending partitions 21 which divide the space behind it into a plurality of article-holding compartments. The ends of the plate 20 are bent inwardly and shaped to form hooks 22 to engage suitable tracks or the like 23 15 in the back casing section. Thus, while the plate 20 is held in place, it may be easily removed if desired and may also be adjusted or moved up or down to different positions in the casing. The spring action of the plate causing a sufficiently tight frictional engagement of the hooks with the tracks to hold the plate in its adjusted positions.

By employing the construction shown and described or a substantial equivalent thereof, a device is provided which will be very desirable for a number of purposes and as excellent results have been obtained from the details disclosed, these details may be followed if desired. However, within the 30 35 scope of the invention as claimed, numerous changes may be made.

I claim:

1. A device of the class described comprising a back plate having a pair of spaced vertical flanges on its front side, and a horizontal ledge between the lower ends of said flanges, a support normally disposed vertically at the front of said flanges and co-operating with said flanges and ledge in forming a compartment for normally holding a writing pad, and connecting means between said flanges and said support permitting the latter to be moved to an operative position. 40 45

2. A device of the class described comprising a back plate having a pair of spaced vertical flanges extending from its front side, and a horizontal ledge between the lower ends of said flanges and extending beyond the outer edges thereof, a support normally disposed vertically and resting upon said ledge at the front edges of said flanges and co-operating with said flanges and ledge in forming a compartment for normally holding a writing pad, and connecting means between said flanges and said support permitting the support to be swung downwardly and outwardly to an operative position. 50 55 60

3. A structure as specified in claim 2; 65 said ledge being formed by a resilient flange normally engaging the support to hold the latter adjacent said flanges.

In testimony whereof I have hereunto affixed my signature.

CARL REINHOLDT KOSITZKY.
